T. G. MARTIN

PARTY LINE MEASURED SERVICE TELEPHONE SYSTEM

Filed Nov. 5, 1919

Att:

UNITED STATES PATENT OFFICE.

TALBOT G. MARTIN, OF CHICAGO, ILLINOIS, ASSIGNOR TO AUTOMATIC ELECTRIC COMPANY, OF CHICAGO, ILLINOIS, A CORPORATION OF ILLINOIS.

PARTY-LINE MEASURED-SERVICE TELEPHONE SYSTEM.

Application filed November 5, 1919. Serial No. 335,920.

To all whom it may concern:

Be it known that I, TALBOT G. MARTIN, a citizen of the United States of America, and a resident of Chicago, Cook County, and 5 State of Illinois, have invented certain new and useful Improvements in Party-Line Measured-Service Telephone Systems, of which the following is a specification.

My invention relates to measured service 10 equipment in combination with telephone systems.

More particularly this invention relates to measured service equipment for use in combination with party line telephone sys- 15 tems.

Heretofore it has been proposed to have a series of meters assigned to a party line, there being provided one meter individual to each of the subscribers on the line. Associated 20 with said meters it has been proposed to use a progressively movable switch for connecting the proper meter with the line whenever one of the party line subscribers make a call.

25 However, this is the first time, as far as applicant is aware, that means of the particular type hereinafter described has been used for associating a subscriber's meter with his line at the time that he is calling.

30 More particularly, this is the first time, for example that a marginal device has been utilized for the purpose of controlling the meters with regard to the line. One of the objects of this invention is to provide such 35 marginal controlling device.

Another object of my invention is to provide details of improvement tending to increase the efficiency and serviceability of a measured service telephone system of the 40 above character.

To accomplish the foregoing and other useful ends my invention consists of means hereinafter set forth and claimed.

In the accompanying drawing Fig. 1 is a 45 diagrammatic representation of a party line, shown at the left, calling another line, shown at the right, through the medium of a non-numerical line switch, a trunk circuit, a numerical switch, such as the first selector re- 50 presented by the dotted square, and a connector switch.

Fig. 2 is a diagrammatic illustration of the application of the invention to a four party line.

55 It might be stated before beginning a de-

tailed description of the means for carrying out the invention, that the non-numerical switch referred to in the drawing may be of the general type shown in United States Patent No. 1,304,369, granted May 20, 1919, to A. J. Ray. Furthermore, the trunk arrangement is in substance the same as the trunk arrangement shown in the same patent between the line switches C and C². 60 Also the first selector may be of the type shown in Patent No. 1,130,784, granted March 9, 1915, to Bernard D. Willis, while the connector may be of the type shown in Patent No. 1,308,749, granted July 1, 1919, to Arthur Bessey Smith. It will be understood, of course, that the called line may be provided with a line switch such as the line switch G shown in the last mentioned patent above. In this connection it may be well to state that the line switch assigned 70 to any subscriber's line is provided with suitable multiples in the connector banks assigned to the particular group to which the calling subscriber belongs. It should be understood that although I have 75 shown only one trunk between the calling line switch and the selector, there are a plurality of such trunks, all of which are accessible to a group of line switches instead of only one line switch as is shown 80 in the drawings, as is well understood, the line switches being usually greater in number than the trunks. Therefore, it follows that each selector switch is multiplied 85 through the trunks of all of the line switches 90 of a given group. Likewise the connector switches which have access to the called subscriber are several in number instead of just one as shown in the drawings, and each connector switch is multiplied to the banks 95 of a series of selector switches instead of to one selector switch only as in the drawings. The master switch shown near the bottom of the drawing is of the type shown in Patent No. 1,304,369 and is for the purpose of controlling the group of line switches that have access to the trunks shown. The telephone is of the usual two-wire automatic type such as shown in the 100 said Patent No. 1,304,369.

105 The following brief statement may help to make the operation of the invention more readily understood:—When the subscriber A makes a call to subscriber B, he does so in the usual way and when subscriber B 110

answers the reversal of battery in the front bridge of the connector switch operates the meter *a* which is individual to the station A. However, if subscriber C makes a call 5 the marginal relay 2 energizes as soon as the subscriber C removes his receiver, which relay in turn energizes the relay 3 associated with the meters 4 and 5 controlled respectively by the magnets *a* and *c*, switching the 10 magnet *c* into circuit in place of the magnet *a*, with the result that when the called subscriber answers the meter 5 is operated instead of the meter 4. This difference is due to the fact that station C does not have 15 the resistance in the line that station A has, as will be described hereinafter.

Referring more in detail to the circuits shown in the drawing, it will be seen that when a subscriber A removes his receiver 20 from the hook the line circuit is closed at the springs 6 and 7. This circuit extends as follows:

Through the polarized relay 8, resistance 9, line conductor 10, line relay springs 11 25 and 12, and through the marginal relay 2 and the line relay 13 to battery. The other side of the line circuit is closed through the transmitter at the telephone and through the other side of the line to ground at the 30 line switch.

The resistance of this circuit is such that the marginal relay 2 does not operate, whereas the line relay 13 does. The result is that a circuit is closed through the pull in 35 winding 14 of the line switch with the result that the connection is extended to the trunk in the usual manner. When the circuit is extended to the trunk the line relay in the selector switch supplies holding 40 ground back over the trunk release conductor 15 in the usual way which ground energizes the hold in winding 16 of the line switch, thereby holding the connection between the line switch and the trunk. From 45 this point on the extension and completion of the connection is obtained by the operation of the dial at the station A, as usual.

It will be seen that when the line switch extends the line to the trunk a circuit is 50 closed through the meter magnet *a* in series with the trunk relay 17. The current in this circuit is not sufficiently strong to energize the meter magnet *a* to cause the meter to register, but it is strong enough to cause the 55 relay 17 to attract its armature. The result is that a circuit is closed through the springs 18 and 19 for applying a guarding potential at the master switch bank to make the trunk busy. Assuming now that the 60 called station is B, upon removing the receiver thereat a circuit is closed through the reversing relay 20 which causes a reversal of current in that section of the talking circuit to the left of the condensers 21. 65 This reversal affects the differential relay

22 in the trunk. This relay 22 does not energize when connection is first extended to the trunk, due to the fact that the current in the right hand winding opposes the current in the left hand winding. However, 70 when the reversal above mentioned occurs the relay 22 energizes with sufficient power to close the contacts 23 and 24. The result is that the right hand winding of the trunk relay 22 is eliminated from the talking circuit by the closure of contact between springs 23 and 24. A further result of the energization of relay 22 is the closure of contacts 25 and 26 which establishes a shunt around the left hand winding of relay 17. 75 This increases the flow of current in the circuit of the meter magnet *a*, which latter then operates to register the call on the meter 4.

The reversal of current also causes the 80 polarized relay 8 at the station A to energize shunting the resistance 9 thereby increasing the flow of current to the transmitter at the station A in order to insure more effective talking. It will be seen that 85 the polarized relay 8 is shunted by a condenser so that the voice currents may avoid the impedance which would be encountered around through the circuit that includes the 90 polarized relay.

If the call for station B had been made from the station C instead of from the station A, as described, reversal of the current by the called party would have operated the meter 5 instead of the meter 4. The 100 difference in action is as follows: Due to the absence in the station C of the resistance, shown in station A shunted by the condenser 27, when the subscriber C removes his receiver not only is the line relay 13 of the 105 line switch C operatively energized, but the marginal relay 2 is also energized with the result that a circuit is established, upon the closure of contacts 28 and 29, through switching relay 3. The result of the energizing of relay 3 is that the meter magnet *c* is substituted for the meter magnet *a* in connection with the conductor 30 that runs to the magnet 17. Otherwise the operation 110 of the line switch is exactly the same as in the preceding case. The result of the substitution of the magnet *c* for the magnet *a* is that upon the reversal of the current the magnet *c* is the one that is operated instead of the magnet *a*.

It will be seen therefore that normally the magnet *a* is connected to the conductor 30, whereas when the subscriber C calls the magnet *c* is connected to the conductor 30.

It will be observed that associated with 125 the switching relay 3 there are a pair of contacts 31 and 32 which are controlled by the switching relay 3. Whenever this relay 3 energizes these contacts are closed and a locking circuit over the trunk release con- 130

ductor 15 is set up in parallel with the bridge cut off winding 16 of the line switch. The object in having this locking circuit is to enable the relay 3 to remain energized 5 after the line switch has extended connection to the trunk. It will be understood that after such connection is made to the trunk the line switch armature 33 opens the circuit between the springs 11 and 12 which 10 cuts off not only the line relay 13 but the marginal relay as well, the two being in series.

It will be seen that when the subscribers 15 are through talking the calling subscriber upon hanging up his receiver will release the connection in the usual manner by opening the line circuit and thereby causing the line relay 34 in the connector switch to fall back. When a connection is broken the line 20 switch is restored and therefore the circuits between the line switch and the trunk are broken with the result that all of the magnets associated with the line switch are de-energized thereby restoring the equipment 25 to normal.

Although I have illustrated my invention in connection with a two-party line, it is applicable just as well to a multi-party line. For example, I may have a line D, Fig. 2, 30 with a number of telephones A', F, E and C', A' and C' corresponding to stations A and C. This line instead of extending through only two relays such as the relays 2' and 13' corresponding to relays 2 35 and 13, Fig. 1, may extend through four relays, the only provision being that when the telephone A' is removed from the switch hook the resistance on the line is so great that only the relay 13', Fig. 2, energizes. 40 When the receiver at the telephone F is removed the relays 2' and 13' energize, Fig. 2. When the receiver at E is removed the relays x, 2' and 13' energize, and when the receiver at C' is removed the relays y, 45 x, 2' and 13' energize. Associated with these relays y, x, 2' are the auxiliary relays 3', 35 and 36, 3' corresponding to relay 3, Fig. 1. The relay 3' it will be seen controls two meter magnets a' and f', the meter magnet a' being individual to the subscriber A', and the meter magnet f' being individual to the subscriber F, etc. It will be seen therefore that with this arrangement I can have a series of telephones on a party line 50 and yet assign to each subscriber a meter individual to him, controlling the assignment of the various meters to the line through the medium of marginal devices.

What I claim as my invention is:

60 1. In a measured service telephone system, a party line, a plurality of telephone stations assigned thereto, a plurality of meters associated with said stations normally disconnected from said line, each station 65 having one of said meters assigned individ-

ually thereto, marginal means for rendering any particular meter operative when the corresponding particular station is used for making a call, and means for operating the connected meter by a reversal of current 70 in the line.

2. In a measured service telephone system, a party line with a plurality of telephone stations assigned thereto, a plurality of meters, one individual to each telephone 75 station, marginal means for determining that when a subscriber calls from a particular station only the meter assigned to that station shall be operated, a non-numerical progressively movable switch assigned to said line for extending connections from said line to another line automatically, and means controlled by the response of the called party for automatically operating the meter determined upon. 80

3. In a measured service telephone system, a party line, a plurality of telephone stations assigned thereto, a plurality of meters associated with said stations normally disconnected from said line, each station 85 having one of said meters assigned individually thereto, marginal means for connecting any particular meter for operation when the corresponding particular station is used for making a call, said meter operated by reversal of current when the called subscriber answers, and a non-numerical progressively movable switch assigned to said line for extending connections from 90 said line to another line automatically. 95

4. In a measured service telephone system, a party line with a plurality of telephone stations assigned thereto, a plurality of meters, one individual to each telephone station, marginal means for determining that when a subscriber calls from a particular station only the meter assigned to that station shall be operated and for determining that when any subscriber calls his particular meter will be operated, a non-numerical progressively movable switch assigned to said line for extending connections from said line to another line automatically, other means for completing a connection with a called telephone line, and means controlled after connection has been extended to the called line for reversing the current on the calling line to cause the meter individual to the station calling to register the call. 100

5. In a measured service telephone system, a party line, a plurality of telephone stations assigned thereto, a plurality of meters associated with said stations normally disconnected from said line, each station having one of said meters assigned individually thereto, marginal means for connecting any particular meter for operating when the corresponding particular station is used for making a call, a non-numerical 110

5
merical progressively movable switch assigned to said line for extending connections from said line to another line automatically, other means for completing a connection with a called telephone line, and means controlled after the connection has been extended to the called line for reversing the current on the calling line to cause the meter individual to the station calling 10 to register the call.

10
15
6. In a measured service telephone system, a party line with a plurality of telephone stations assigned thereto, a plurality of meters, one individual to each telephone station, marginal means for determining that when a subscriber calls from a particular station only the meter assigned to that station shall be operated and for determining that when any subscriber calls his particular meter will be operated, a non-numerical progressively movable switch assigned to said line for extending connections from said line to another line automatically, other means for completing a connection with a 20 called telephone line, and means controlled after connection has been extended to the called line for reversing the current on the calling line to cause the meter determined upon by the marginal device to register 30 the call.

30
35
7. In a measured service telephone system, a party line, a plurality of telephone stations assigned thereto, a plurality of meters associated with said stations normally disconnected from said line, each station having one of said meters assigned individually thereto, marginal means for connecting any particular meter with the line when the corresponding particular station is used 40 for making a call, a non-numerical progressively movable switch assigned to said line for extending connections from said line to another line automatically, other means for completing a connection with a called 45 telephone line, and means controlled after the connection has been extended to the called line for reversing the current on the calling line to cause the meter determined upon by the marginal device to register 50 the call.

50
55
8. In a measured service telephone system, a two-party line, a meter at the exchange for each station on the line, one of said meters being normally connected for operation, a line relay individual to said line and adapted to be energized over the two sides of said line in series when the receiver is removed at either station, a marginal relay in series with said line relay, a resistance in the line circuit at one of the stations for preventing said marginal relay 60 from operating when the line relay is operated, means for substituting the normally disconnected meter for the normally connected meter when the marginal relay is

operated, and means for automatically operating the connected meter.

9. In a measured service telephone system, a two-party line, a meter at the exchange for each station on the line, a line relay individual to said line and adapted to be energized over the line when the receiver is removed at either station, a marginal relay in series with said line relay, a resistance in the line circuit at one of said stations for preventing said marginal relay from operating when the line relay is operated, means controlled by said marginal relay for determining which of said meters is to be operated to register each call, and a single means for causing said resistance to be short circuited during a conversation involving the associated station and for also effecting the operation of the connected meter. 75 80 85

9. In a measured service telephone system, a two-party line, a meter at the exchange for each station on the line, a line relay individual to said line and adapted to be energized over the line when the receiver is removed at either station, a marginal relay in series with said line relay, a resistance in the line circuit at one of said stations for preventing said marginal relay from operating when the line relay is operated, means controlled by said marginal relay for determining which of said meters is to be operated to register each call, a relay at the station having said resistance for eliminating the said resistance from the talking circuit when the call originates at said station, and a single means for operating said relay and for controlling the operation of the connected meter. 90 95 100

10. In a measured service telephone system, a two-party line, a meter at the exchange for each station on the line, a line relay individual to said line and adapted to be energized over the line when the receiver is removed at either station, a marginal relay in series with said line relay, a resistance in the line circuit at one of said stations for preventing said marginal relay from operating when the line relay is operated, means controlled by said marginal relay for determining which of said meters is to be operated to register each call, a relay at the station having said resistance for eliminating the said resistance from the talking circuit when the call originates at said station, and a single means for operating said relay and for controlling the operation of the connected meter. 105 110 115 120 125

Signed by me at Chicago, Cook County, Illinois, this 31st day of October, 1919.

TALBOT G. MARTIN.
